UNITED STATES PATENT OFFICE.

FRANK C. MEDICK, OF COLUMBUS, OHIO.

DESIGN FOR A PHOTOGRAPH MOUNT.

Application filed January 7, 1924. Serial No. 8,261. Term of patent 14 years.

To all whom it may concern:

Be it known that I, FRANK C. MEDICK, a citizen of the United States, residing at Columbus, in the county of Franklin and State of Ohio, have invented a new, original, and ornamental Design for Photograph Mount, of which the following is a specification, reference being had to the drawing, forming part thereof.

The design consists of a central panel and two smaller side panels, each having straight sides and a straight bottom and a top formed on a comparatively broad curve, character-

ized by the fact that the outer upper corners of the side panels and the center of the top of the central panel are located on substantially the same arc of a circle when the folds of the mounting are in a horizontal position, with the bottoms of the panels extending on the same line.

The figure is a front elevation of a photograph mount, showing my new design.

I claim:

The ornamental design for a photograph mount as shown and described.

FRANK C. MEDICK.
